UNITED STATES PATENT OFFICE

159,043

PORTABLE POWER SAW

Aileen Bushnell, Aurora, Ill., assignor to Independent Pneumatic Tool Company, Aurora, Ill., a corporation of Delaware

Application August 2, 1949, Serial No. 4,255

Term of patent 14 years

(Cl. D93—3)

To all whom it may concern:

Be it known that I, Aileen Bushnell, a citizen of the United States, residing at Aurora, in the county of Kane, State of Illinois, have invented a new, original, and ornamental Design for a Portable Power Saw, of which the following is a specification, reference being had to the accompanying drawing forming, a part thereof, wherein:

Figure 1 is a side elevational view of a portable power saw showing my new design; Figure 2 is a rear elevational view of the same; Figure 3 is a top plan view of the same; Figure 4 is an elevational view of the other side of the saw; and Figure 5 is a front elevational view of the same.

I claim:

The ornamental design for a portable power saw, substantially as shown.

AILEEN BUSHNELL.
